UNITED STATES PATENT OFFICE.

JACOB KAPLAN AND ISRAEL LACK, OF BROOKLYN, NEW YORK.

VALVE.

1,301,948.

Specification of Letters Patent. Patented Apr. 29, 1919.

Application filed April 25, 1917. Serial No. 164,503.

To all whom it may concern:

Be it known that we, JACOB KAPLAN and ISRAEL LACK, both citizens of the United States of America, residing in the borough 5 of Brooklyn, county of Kings, city and State of New York, have invented certain new and useful Improvements in Valves, of which the following is a specification.

This invention relates to valves and aims 10 to provide improvements therein.

The present invention provides what may be called a "packless" valve and is especially applicable to use in vacuum systems and in house steam or hot water heating systems.

15 A flexible diaphragm is placed between the operating part and the valve proper; according to the present invention this diaphragm is so arranged and related to the other parts of the device that a minimum of 20 movement thereof is required in opening or closing the valve, so that the strain on the diaphragm, and consequent liability to breaking or cracking, is extremely slight.

The general construction of the valve is 25 simple.

The invention will be more fully described in connection with the accompanying drawings, illustrating one embodiment thereof.

In said drawings,—

30 Figure 1 is a vertical section illustrating the parts in position corresponding to the closed position of the valve;

Fig. 2 is a similar view illustrating the parts in the position corresponding to the 35 open position of the valve;

Figs. 3 and 4 are detail views, showing respectively a plan view and an elevation of a part of the handle;

Fig. 5 illustrates in plan and elevation a 40 key-plate used to secure the handle to the body of the valve;

Fig. 6 is a detail view showing in elevation the front of the valve proper and the end of its operating lever;

Fig. 7 is a top plan view of the valve, 45 with the handle removed;

Fig. 8 is a detail view illustrating the mounting of the lever which operates the valve proper;

Fig. 9 is a detail view of a guide ring.

Referring to said drawings, numeral 1 indicates a valve casing, preferably made in two parts, 2 and 3, connected, for example, by a threaded sleeve 4.

50 Numeral 5 designates the valve proper

within the valve casing. The valve proper 5 is conveniently formed with a stem which may be guided by a guide ring 7 inserted in the valve casing. The valve proper also preferably has a sleeve 8 thereon which telescopes upon a projection 9 from the inner side of the valve casing. The sleeve 8 and rod 9 preferably have shoulders 10 and 11 thereon, between which may be arranged a spring 12 adapted to normally press the 60 valve proper to its seat. The projection or rod 9 may be conveniently formed with a stub 13 which fits within a socket 14 in the valve casing. The spring 12 acts to hold the stub 13 in the socket 14, and hence to hold 65 the rod or projection 9 in place.

The valve proper 5 is moved to and from its seat by means of a pivoted lever 15, having a long arm 16 and a short arm 17, the lever being preferably provided with knife 75 edge trunnions 18 fitting within bearings 19 formed upon the inner side of the casing 1 (Figs. 7 and 8). The long arm 16 of the lever 15 is bifurcated at its end (Figs. 1 and 6), and fits around the valve sleeve 8 between the back face of the valve and the flange 11, and carries the valve proper with it, as it is moved toward and away from the seat.

The short arm 17 of the lever 15 is preferably provided with a roller 20 which fits within the cam groove 21 (Figs. 1, 2 and 3) within a rotatable cap or plate 22. This cam groove is formed with a gradual rise or incline, the frictional force between the 80 lever and groove being greater than the force component parallel to the groove. The plate thereby retains its rotated position against the force exerted by the lever 16, 17 under the stresses of the diaphragm 27 and 95 spring 12, tending to turn the plate to initial position. The cap or plate 22 is conveniently provided with a wooden heat insulating covering 23. The plate 22 may be conveniently keyed to the casing 1 by means of key-plates 100 24 (Fig. 5), fitting in an annular groove 25 (Fig. 4) in plate 22, and in slots 26 (Fig. 8), formed in the casing 1, the plates 24 being conveniently held in place by the insulating covering 23.

Between the operating lever 15 and the casing 1 there is placed a flexible diaphragm 27. This diaphragm is preferably attached to the lever 15 at or near its pivotal plane. The diaphragm is preferably a tubular cor- 110

rugated diaphragm and is preferably tapered or reduced in diameter at the point where it is connected to the lever 15. It may be attached to the lever in any suitable manner, 5 it being here shown as having its edge portions fitting within a groove 28 cut within the lever and the material swaged down upon it. The opposite end of the diaphragm 27 is preferably formed with a flange 30, and 10 this flange 30 is conveniently clamped between the portions 2 and 3 of the valve casting. The construction of the diaphragm as thus described, and its connection to the lever and casing facilitates the easy assembling 15 of the device.

Operation: To open the valve, the plate 22 is turned, and the groove 21 therein causes the lever 15 to rock in its bearings 19. A slight movement of the short arm 17 20 of the lever gives multiple movement to the long arm 16 of the lever. A comparatively slight amount of movement of the short arm 17 of the lever 15 in the proper direction is thus sufficient to open widely the 25 valve proper 5. The gradual rise of the cam groove 21 enables the lever to be moved with an ordinary effort against a fairly strong pressure of the spring 12.

Moreover, the diaphragm, being connected 30 to the lever near its pivotal plane, undergoes a movement which is relatively slight, as compared with the amount of movement of the end of the arm 16 of the lever. This slight movement of the diaphragm being 35 distributed among the several corrugations of the diaphragm, causes a very slight movement of the diaphragm, and hence exerts very little strain upon the diaphragm. There is hence little danger of the dia- 40 phragm breaking under use.

To close the valve 5 the cap 22 is simply rotated in a direction opposite to the opening movement. The movement of the valve proper 5 is assisted by the pressure of the 45 spring 12.

It will thus be seen that the valve is of 50 very simple construction, is susceptible of being readily assembled, and enables the diaphragm to be used under conditions which entail very little movement thereof and strain thereon.

The inventive ideas may receive other mechanical expressions than those herein specifically illustrated and described.

55 What is claimed is:—

1. A valve, comprising a valve proper, a pivoted lever for operating said valve proper, and a tubular corrugated diaphragm for packing said valve, attached to said lever near its pivotal plane.

60 2. A valve, comprising a valve proper, a pivoted lever for operating said valve proper, and a tubular corrugated diaphragm for packing said valve, attached to said lever near its pivotal plane, said diaphragm

being reduced in diameter near its point of connection to the lever.

3. A valve normally spring pressed, comprising a valve proper, a pivoted lever for opening said valve proper, and a diaphragm 70 for packing said valve, attached to said lever, said lever having a long arm and a short arm, the long arm being adapted to impart opening movement to the valve proper, and a cam-plate contacting with 75 said short arm for operating said lever.

4. A valve normally spring pressed, comprising a valve proper, a pivoted lever for opening said valve proper, and a tubular corrugated diaphragm for packing said 80 valve, attached to said lever near its pivotal plane, said lever having a long arm and a short arm, the long arm being adapted to impart opening movement to the valve proper.

5. A valve normally spring pressed, comprising a valve proper, a pivoted lever for opening said valve proper, and a tubular corrugated diaphragm for packing said 90 valve, attached to said lever near its pivotal plane, said lever having a long arm and a short arm, the long arm being adapted to impart opening movement to the valve proper, and a cam-plate contacting with 95 said short arm for operating said lever.

6. A valve normally spring pressed, comprising a valve proper, a pivoted lever for opening said valve proper, and a tubular corrugated diaphragm for packing said valve, attached to said lever near its pivotal 100 plane, said diaphragm being reduced in diameter near its point of connection to the lever, said lever having a long arm and a short arm, the long arm being adapted to impart opening movement to the valve 105 proper, and a cam-plate contacting with said short arm for operating said lever.

7. A valve, comprising a casing, a valve proper, a pivoted lever for operating said valve proper, and a tubular corrugated dia- 110 phragm for packing said valve, attached to said lever, said diaphragm having a flange and said casing being made in two tubular parts adapted to house said tubular dia- 115 phragm, said flange being adapted to be clamped between said two parts of the casing.

8. A valve, comprising a casing, a valve proper, a spring, a lever for opening said valve and a projection for guiding the 120 spring, said casing and projection having parts fitting together, and said valve and projection having parts telescoping with each other, said spring pressing said valve to its seat and pressing said projection 125 against the casing.

9. A valve comprising a valve proper, a pivoted lever for operating said valve proper, a diaphragm for packing said valve, a casing inclosing said parts, and a rotatable 130

plate at the end of said casing having a cam groove in which one end of said lever engages, said groove having a gradual incline, the frictional force between lever and groove being greater than the force component parallel to the groove whereby the plate retains its rotated position against the force

exerted by the lever tending to turn the plate to initial position.

In witness whereof, we have hereunto signed our names.

JACOB KAPLAN.
ISRAEL LACK.
